UNITED STATES PATENT OFFICE

ANTHONY LUISA-VISSLAT, OF BRIDGEVILLE, PENNSYLVANIA

TIE-PLATE, RAIL, AND RAIL ANCHOR

Application filed September 4, 1931. Serial No. 561,123.

This invention relates to tie plates, rails, and rail anchors, for use in railway track construction. More particularly the invention relates to tie plates and rails specially constructed to have cooperative interlocking relation, whereby the rail may be prevented from creeping with respect to the plate.

An object of the invention is to provide an improved tie plate which will be interlocked with a special rail base to prevent creeping. A further object is to provide a special rail base having abutments adapted to cooperate with a tie plate and/or retaining spikes to prevent creeping of the rail.

As is well known by those familiar with track construction, there is a tendency of rails to creep along the track in the direction of the travel of trains passing thereover. This creepage has many objectionable results, and it is customary to prevent it by the application of anchors to the rails. Usually the anchors heretofore used are in the form of spring clamps applied to the rails in such position that they will abut against adjacent ties. Thereafter creepage of the rail can result only by slippage of the anchor on the rail, by movement of the tie, or by cutting into the tie of the rail anchor. These devices are quite expensive in themselves, and they are expensive to apply and maintain.

It is the custom in track construction to lay the rail on a tie plate positioned on top of a wooden tie embedded in the track ballast. Sometimes rails are laid on the ties without plates. The tie plates are punched to receive spikes or screws adapted to fasten them to the ties, and usually they have a retaining rib or ribs adapted to prevent lateral slippage of the rail on the plate.

The present invention has for its principal object a cooperative construction of a tie plate and rail base whereby there may be provided an interlock between the rail and plate which will prevent rail creepage.

Referring to the drawing, Fig. 1 shows in perspective a preferred form of my tie plate and rail construction; Fig. 2 shows a modification of the tie plate in that only one interlocking shoulder is provided thereon; Fig. 3 shows a modification in which interlocking

surfaces are provided on the under side of the rail and on the upper side of that portion of the plate on which the rail seats; Fig. 4 shows a modification in which the side corrugations of Fig. 1 and the bottom corrugations of Fig. 3 are both used; and Fig. 5 shows a perspective view of the underside of a rail having projections and recesses on both sides and bottom of the base.

The preferred form of my invention is shown in Fig. 1, wherein a rail R is shown seated in a special tie plate P. It will be understood that this plate is normally positioned longitudinally upon a conventional wooden tie T, and spiked or otherwise fastened thereto. The tie plate has an intermediate recessed rail seating portion 1, with either a level or sloping base, and perforated end portions 2 and 3. Holes 4, 5, 6, 7, 8, and 9 are provided in the portions 2 and 3 to receive spikes, screws, or other attaching members, according to whether the tie is of wood, concrete, composition, metal, etc.

The shoulders bounding the recessed portion 1 are formed with undulating or vertically corrugated walls 10 and 11 having recesses 12 and projections 13.

The particular size and shape of the projections and recesses 12 and 13 may be widely varied. They may be comparatively large and of true arcuate shape, as shown in Fig. 1, or they may be reduced to quite small angular serrated projections and recesses, or any intermediate shape.

The spike holes 5, 6, 7, and 9 are preferably positioned so that the shanks of the spikes passing therethrough will be positioned near the extremity of one of the projections 13.

The rail R cooperating with this special tie plate has the vertical edges of its base flanges corrugated to form recesses 15 and projections 16 complementary to those in the tie plate shoulders. Consequently when the plate is placed on a tie and the rail positioned thereon as shown in Fig. 1, and the plate fastened to the tie by spikes or other means, the rail will be securely fastened to the tie plate and prevented from movement relative thereto in any direction. The interlocking recesses and projections 12 and 13 on the

plate, and the cooperating complementary projections and recesses 15 and 16 on the rail form a positive interlock so that the rail can not creep.

- 5 By having such an interlock between the rails and plates at every tie the creeping tendency is distributed over the entire track, and no undue strain is put upon any particular tie, as in the present practice, wherein 10 anchors are applied at intervals spaced several ties apart.

In Fig. 2 a modification is shown in that the plate P^1 has only one shoulder, adapted to be on the outside or inside of the track. 15 This has recesses and projections 12 and 13 as in the case of the two shoulders of Fig. 1. The rail adapted to cooperate with the plate P^1 has recesses 15 and projections 16 in the flanged edges, so that the adjacent edge of 20 the rail interlocks with the corrugated shoulder of this modified tie plate.

At the other edge of the rail, the spike holes are positioned so that the shanks of the spikes will lie in the recesses 15 in the rail base, thus providing a positive interlocking abutment to prevent creeping of the rail, as well as holding the rail against the interlocking shoulder at the other side of the plate.

A further modification is shown in Fig. 3, 30 in that the intermediate rail-receiving portion 1a of the plate P^2 has transverse ribs 20 and grooves 21 therein. The under side of the rail adapted to cooperate with this modified tie plate has corresponding recesses 22 and ribs 23 formed in the bottom, as shown in Fig. 5, adapted to seat in and interlock with the ribs and recesses in the portion 1a of the tie plate P^2 .

Any of the forms shown in Figs. 1, 2, or 3 40 will ordinarily be sufficient to give a positive interlocking of the rail and tie plate, but if desired the forms shown in Figs. 1 and 3 may be combined. That is to say the tie plate may have both the corrugated rail-receiving portion 1a and the corrugated bounding shoulders in combination therewith similar to the showing of Fig. 1. Fig. 4 shows a combination of the interlocks of Figs. 1 and 3. The plate P^3 has a rail-receiving recess 45 1b, the face of which has transverse ribs 20 and grooves 21, while its side walls have recesses 12a and projections 13, adapted to cooperate with complementary recesses 22 and ribs 23 on the base of the rail, and flange projections 16 and recesses 15 on the rail, respectively. Thus there is both a side and bottom interlock between rails and ties.

Use of this invention prevents slippage of the rail on the ties, and therefore permits longer rails to be used.

The many uses and advantages of this device will be apparent to those familiar with the art.

I claim:

- 65 1. In railroad track construction, the com-

bination of a tie plate having a rail-receiving recess across the face thereof, the bottom of the recess being divided into alternate ribs and recesses, and a rail adapted to seat upon the said plate in said rail-receiving recess and having recesses and ribs adapted to cooperate and interlock with the said ribs and recesses of the tie plate, whereby to form a positive interlock between the rail and tie plate.

2. In a railroad track construction, the combination with a rail having its under side formed into transverse projections and recesses, and the edges of its base flanges formed into vertical projections and recesses, with a tie plate having a rail-receiving depression extending across the face thereof, said depression having recesses and projections in its upper face adapted to cooperate with the projections and recesses in the bottom of the rail, and having its side wall formed into recesses and projections adapted to cooperate and interlock with the projections and recesses in the edges of the rail flanges, whereby to provide a positive interlock between the rail and tie plate to prevent creepage of the rail with respect to the plate.

In testimony whereof, I sign my name,

ANTHONY LUISA-VISSLAT.
